UNITED STATES PATENT OFFICE.

LOUIS C. HILLER, OF MERIDEN, CONNECTICUT, ASSIGNOR TO THE MERIDEN SILVER PLATE COMPANY, OF SAME PLACE.

DESIGN FOR A METAL BORDER.

SPECIFICATION forming part of Design No. 21,698, dated July 5, 1892.

Application filed May 31, 1892. Serial No. 435,083. Term of patent 3½ years.

To all whom it may concern:

Be it known that I, LOUIS C. HILLER, of Meriden, in the county of New Haven and State of Connecticut, have invented a new 5 Design for a Metal Border (Case B;) and I do hereby declare the following, when taken in connection with accompanying drawing, to be a full, clear, and exact description of the same, and which said drawing constitutes part of 10 this specification, and represents a section of the border, the border being made up of a succession of such sections.

This invention relates to a design for a metal border adapted for various purposes; and it 15 consists in the ornamentation as shown in the accompanying illustration.

The border is of rococo character, and represents a succession of floriated scroll-work

branching both ways from a central shield-like ornament, which is in itself surrounded 20 by the representation of scrolls, which form a connection between the shield and the ornamentation branching therefrom, and as shown in the accompanying illustration.

I claim—

25 The design for a metal border, as herein described, and shown in the accompanying illustration.

In testimony whereof I have signed this specification in the presence of two subscriv- 30 ing witnesses.

LOUIS C. HILLER.
